UNITED STATES PATENT OFFICE

133,710

DESIGN FOR A GUMMED PAPER TAPE DISPENSER

Harry F. Gilliam, Kansas City, Mo.

Application March 2, 1942, Serial No. 106,047

Term of patent 3½ years

To all whom it may concern:

Be it known that I, Harry F. Gilliam, a citizen of the United States, residing at Kansas City, in the county of Jackson and State of Missouri, have invented a new, original, and ornamental Design for a Gummed Paper Tape Dispenser, of which the following is a specification, reference being had to the accompanying drawing, forming a part thereof.

Fig. 2 is a rear perspective view thereof.

I claim:

The ornamental design for a gummed paper tape dispenser, as shown.

HARRY F. GILLIAM.
